(57) **CLAIM**

The ornamental design for an inkjet printer with fixed sheet feeder, substantially as shown and described.

DESCRIPTION

FIG. 1 is a perspective view of an inkjet printer with fixed sheet feeder in accordance with the present invention;

FIG. 2 is a front elevational view thereof;

FIG. 3 is a rear elevational view thereof;

FIG. 4 is a top plan view thereof; and,

FIG. 5 is a right side elevational view thereof, left side elevational view being a mirror image.
